US00D807502S

(12) **United States Design Patent** (10) **Patent No.:** **US D807,502 S**
(45) **Date of Patent:** **** Jan. 9, 2018**

(54) **ENTERAL SYRINGE**

(71) Applicant: **NEOMED, INC.**, Woodstock, GA (US)

(72) Inventors: **Benjamin M. Davis**, Woodstock, GA (US); **Aaron N. Ingram**, Canton, GA (US); **John Burke**, County Roscommon (IE); **Mark M. Costello**, Co. Mayo (IE)

(73) Assignee: **NEOMED, INC.**, Woodstock, GA (US)

(**) Term: **14 Years**

(21) Appl. No.: **29/519,107**

(22) Filed: **Mar. 2, 2015**

(51) LOC (11) Cl. **24-02**

(52) U.S. Cl.

USPC **D24/130**

(58) **Field of Classification Search**

USPC D24/112-114, 108, 133, 130, 127, 186; 606/181, 185; 604/264, 272, 187, 181, 604/184, 227

CPC A61M 5/178; A61M 3/00; A61M 5/20; A61M 5/31; A61M 5/3146; A61M 5/3129; A61M 5/3148; A61M 5/315

(57) **CLAIM**

The ornamental design for an enteral syringe, substantially as shown and described.

DESCRIPTION

FIG. 1 is a perspective view of an enteral syringe showing our new design.

FIG. 2 is a front elevation view thereof.

FIG. 3 is a rear elevation view thereof.

FIG. 4 is first side elevation view thereof.

FIG. 5 is a second side elevation view thereof.

FIG. 6 is a first end elevation view thereof; and,

FIG. 7 is a second end elevation view thereof.

The broken lines show portions of the design that form no part of the claimed design.

1 Claim, 4 Drawing Sheets
